UNITED STATES PATENT OFFICE.

FRANK KRAEMER, OF CHICAGO, ILLINOIS, ASSIGNOR, BY MESNE ASSIGNMENTS, TO
MAX HARRIS, OF PITTSBURGH, PENNSYLVANIA.

ELECTRIC FLAT-RATE CONTROLLER.

1,100,832.

Specification of Letters Patent. Patented June 23, 1914.

Application filed March 14, 1907, Serial No. 362,398. Renewed August 8, 1913. Serial No. 783,839.

To all whom it may concern:

Be it known that I, FRANK KRAEMER, a citizen of the United States, and a resident of Chicago, in the county of Cook and State 5 of Illinois, have invented certain new and useful Improvements in Electric Flat-Rate Controllers, of which the following is a full, clear, and exact specification.

My invention is intended primarily for 10 use with electric plants furnishing current at a flat rate; that is to say, a rate based upon the average or maximum number of lights, motors or other translating devices or current consumers used at any given time 15 by the subscriber or patron, instead of a rate based upon the watt or kilowatt hour; and its object is to open or break intermittently the loop, branch or derived circuit in which the lamps, motors or translating devices 20 of a plant, building or apartment are located, whenever it is attempted to add fraudulently or illicitly to the authorized number; such persistent intermittence of the current supply being continued until the 25 illicit use thereof is abandoned; either by the cutting out or absolute removal of the extra current consumer. To this end, the current supplying the derived or work circuit is passed through a series magnet, 30 which when the current is rendered excessive by the demands of the additional load imposed by extra and illegitimate consuming devices, overcomes a mechanical resistance and closes a switch that energizes 35 another magnet that cuts off the supply of current to the lights, etc., from the leads or mains, all as will be fully explained in the specification, and the novel elements and combinations of elements employed therein 40 particularly pointed out in the claims.

To illustrate my invention, I annex hereto two sheets of drawings, in which the same reference characters are used to designate identical parts in all the figures, of which,—

Figure 1 is a front elevation of the apparatus embodying my invention; Fig. 2 is a side elevation of the same; Fig. 3 is a vertical section on the line A—A of Fig. 2; Fig. 4 is a top plan view showing the adjusting mechanism for regulating the number of power-consuming units to be controlled; and Fig. 5 is a diagrammatic view showing the currents in the apparatus under normal conditions in full lines, and under abnormal 55 conditions in dotted lines.

The apparatus is mounted on a base plate 9, which may be of marble, slate, or other suitable insulating material, and it will be understood that the complete apparatus is located in a casing, which is locked to everybody except the party furnishing the power, so that it cannot be tampered with by the consumer to fraudulently increase the supply of current to which he is entitled. The leading-in wire 10 passes through the casing, 60 and is secured to the binding post or connection 11 in any customary manner. From this post, the current is preferably passed by the wire 12 to the clips 13 and 14 adapted to receive the fuse 15. From the upper clip 65 14, the current passes through the wire 16 into the coils 17 of the series magnet 18, which is attached to the base by ears 19 secured to the top disk 20 of the spool, and by ears 21 secured to the bottom disk 22 of the 70 spool; the two disks being connected by the tube 23, which serves as a guide or channel for the cores of the ampere magnet 18 and the circuit-breaking magnet 24; both of these magnets preferably taking the form of 75 solenoids mounted in axial alignment with each other, and, as seen, arranged upon a single spool, the two magnets being separated by the disk 25. The disks 26, 27, 28 and 29 are, of course, of insulating material. 80 From the coils 17 of the ampere magnet, the current passes by the wire 30 to the binding post 31, through the lower portion of the conductor strip 32 to the binding post 33, and thence by the wire 34 to the bracket-shaped contact and binding post 35. From 85 here it passes by the metallic switch bar 36 to the similar binding post 37, whence it passes by the wire 38 to one side of the work circuit indicated in Fig. 5 by the lamps 39, and thence by the wire 40 to the binding post 41, whence it passes by the wire 42 to the binding post 43, whence it passes by the wire 44 back to the other side 90 of the generator or mains. When, however, the number of lamps or other translating devices in the work circuit is increased above the allowed number, so that the demands thereof increase the current necessary, all of which must pass through the ampere 100 magnet, the pull of the magnet on its core 45, (which is suspended from the ear 46 on the switch lever 47 by the link 48 of insulating material) is sufficient to overcome the pull of the spring 49, which tends to 105 110

hold the core in the elevated position shown in full lines.

For the purposes of accurate adjustment, as is necessary for allowable variations in the number of lamps or other units to be employed, means are provided for carefully adjusting the tension of the spring, and, for this purpose, the forward end of the spring is secured to the lug 50 projecting down-wardly from the bottom of the adjustable bar 51, which is slotted at 52, so that by co-operating with the pin 53 projecting upward from the lever 47, it can be guided and held in any position of adjustment by means of the set screw 54 passing through the slot 52 and threaded into the lever 47. This is the adjustment employed in changing the instrument, after it is sent out, from one number of lamps or translating units to another. Another adjustment employed at the time the apparatus is assembled in the shop, consists of the set screw 55, which is threaded through the supporting ear 56 extending from the standard 57, in which the lever 47 is pivoted, as at 58. After the screw has been adjusted to secure the desired tension, the lock nuts 59 are tightened up to secure it rigidly. It will be apparent that as the screw is lowered from the position shown, the tension of the spring 49 is increased. When the solenoid core 45 is pulled down against the resistance of the spring 49, the contact end of the lever 47 engages the contact piece or bracket 60, which projects from the base, and is electrically connected with the upper end of the strip 32. The current now passes from the strip 32 through the contact 60, through the lever 47, thence through the conducting strip 61 electrically connected with the supporting bracket 57 of the lever 47, to the binding screw 62, thence to the coils 63 of the switch-breaking magnet, through said coils and through the wire 64 forming a continuation thereof, to the binding screw 65, thence through the strip 66 to the binding screw 67, thence through the wire 68 to the binding post 41, thence through the wire 42 to the binding post 43, and thence by the wire 44 to the generator or other side of the main, thus completing the circuit in shunt with the work circuit, through the circuit-breaking magnet. This, of course, energizes the solenoid circuit-breaking switch-magnet 24, and draws up the core 69 of said magnet, and also draws down the auxiliary core 70, which is adjustably supported from the core 45 of the ampere magnet by the rod 71 connected thereto and threaded into the core 45. The object of this supplemental core 70 is to completely and more firmly operate the switch lever 47, which is provided at its outer end with the preliminary contact member 72, which consists of a strip of thin brass of the shape shown, which strip contacts with the

rounded edge of the contact member 60 as soon as the core 45 is drawn down. When the magnet 24 is energized, the additional pull of the core 70 serves to bend the curved portion of the contact member 72 outward enough so that the lever 47 can be drawn all the way down so that the body of the lever rests directly on the top of the contact 60, so that the circuit is closed directly through the lever without the intermediate contact member 72. One object of this construction is to insure a clean contact between the lever 47 and the contact bracket 60. When the circuit is opened or closed at this point, any sparking that occurs must necessarily occur between the spring contact member 72 and that portion of the contact bracket 60 with which it engages. Now when the lever 47 is drawn the rest of the way down, so that the body of the lever contacts directly with the bracket 60, the spring member 72 wipes over the portion of the bracket 60 on which the sparking occurs, and automatically cleans both contacts from the effect of such sparking. Of course, no sparking occurs between the main body of the lever 47 and the contact 60.

The lower end of the core 69 carries the switch bar 36, and this switch bar 36 is provided on each end with the spring contact members 73, which correspond in shape to and co-operate with the contact brackets 35 and 37 in just the same manner and for the same purpose as the contact 72 co-operates with the contact bracket 60. When the switch bar 36 is raised by the rising of the core 69, of course, the circuit through the lamps or work circuit is broken, and the entire circuit through the apparatus is as indicated diagrammatically by the dotted lines in Fig. 5. The upward movement of the core 69 is resisted and the time of said movement lengthened by reason of the piston 74 carried by the stem 75, which stem is supported and moved by the core 69, with which it is adjustably connected, preferably by having the reduced portion 76 threaded into an aperture in the lower portion of the core. The piston 74 is preferably made up of a rubber disk 77 secured between washers 78 and 79, and an aperture 80 opening into the dashpot 81 at the bottom thereof serves to retard the speed of the ascent of the piston. If it is desired to regulate the speed of the ascent, this can be effected by means of the set-screw valve 82 threaded into a lug on the dashpot barrel so as to partly close the aperture 80. The dashpot is supported from the base 9 by the bracket 83 secured to said base.

Substantially at the end of the upward movement of the core 69, its upper end strikes the lower end of the supplemental core 70, as indicated in the dotted-line position of said cores in Fig. 3, and positively

lifts said core against the pull of the magnet 24, so as to positively raise the switch lever 47 and break the circuit at that point. The circuit is now broken throughout the entire apparatus, the circuit through the main branch being broken by reason of the bar 36 being raised, and the circuit through the shunt branch being broken by reason of the lever 47 being raised. This condition existing, gravity comes into play and causes the gradual descent of the core 69 and the associated switch bar 36 and piston 79, the descent being slowed up by the resistance offered by the dashpot until the spring contacts 73 just strike the contact brackets 35 and 37. At this time, the disk 77 of the piston reaches the enlarged lower portion formed by the annular offset 84, so that the piston and its connected parts can descend rapidly for the rest of the movement, as is necessary to make the desired quick contact of the switch bar 36 with the brackets 35 and 37 to prevent sparking.

It is desirable to have guiding means to prevent the rotation of said switch bar, and, for this purpose, I provide vertical strips 91 of fiber or other insulating material, 91, which are secured to the front of the brackets 35 and 37, as clearly shown in Figs. 1 and 2.

From the foregoing description it will be apparent that so long as an overload continues, the work circuit will be opened and closed at intervals, producing an annoyance to the consumer that will cause him to remedy the difficulty at once by turning off the extra light or other translating unit which has been added.

It will also be apparent to those skilled in the art, that I have produced a simple and efficient construction by which the amount of current used can be very accurately regulated, and which in practice has been found to be extremely efficient and free from liability to get out of order or necessitate repairs.

While I have shown my novel switch mechanism arranged specifically for use as a flat rate controller, it will be understood that it is capable of other uses, and that where the claims are not limited to a flat rate controller, I intend to cover the switch applied to any use desired.

While I have shown and described my invention as embodied in the form which I at present consider best adapted to carry out its purposes, it will be understood that it is capable of modifications, and that I do not desire to be limited in the interpretation of the following claims except as may be necessitated by the state of the prior art.

That which I claim as new, and desire to secure by Letters Patent of the United States, is,—

1. In a flat rate controller, the combina-

tion of a series magnet, a main leading thereto, a work circuit fed through the series magnet, an outgoing main leading from the second side of the work circuit, a switch closed by an abnormal load or current 70 through the series magnet, a second magnet connected up in series with the first magnet by the closing of the switch to cut out the work circuit only, and means operated by said second magnet to open said switch and 75 permit the automatic restoration of the current through the work circuit, said means comprising a member interposed between, and carried by one of the armatures of said magnets so that through said member the 80 armature of the second magnet operates by its movement to move the armature of the series magnet to positively open the switch closed by the attraction of said armature.

2. In a flat rate controller, the combination of a series solenoid magnet, a main leading thereto, a work circuit fed through the series magnet, an outgoing main leading from the second side of the work circuit, a switch connected with the core of the series 90 magnet and closed by an abnormal load or current through said magnet, a second solenoid magnet in alinement with the series magnet connected up by the closing of the switch to cut out the work circuit only, and 95 a supplementary core for the second magnet carried by and forming a physical extension of the core of the series magnet, the main core of the second solenoid being adapted to engage its supplementary core and thereby open said switch positively and permit the automatic restoration of current through 100 the work circuit.

3. In a flat rate controller, the combination of the series solenoid magnet, a main 105 leading thereto, a work circuit fed through the series magnet, an outgoing main leading from the second side of the work circuit, a switch connected with the core of the series magnet and closed by the abnormal load or 110 current through said magnet, a second solenoid magnet in alinement with the series magnet connected up by the closing of the switch to cut out the work circuit only, a supplementary core for the second magnet 115 carried by and forming a physical extension of the core of the series magnet, and mechanism for adjusting the position of the supplementary core of the second magnet, the main core of the second solenoid being 120 adapted to engage its supplementary core to open said switch positively and permit the automatic restoration of current through the work circuit.

4. In a flat rate controller, the combination of a series solenoid magnet, a main leading thereto, a work circuit fed through the series magnet, an outgoing main leading from the second side of the work circuit, a switch connected with the core of the series 125 magnet 130

4 magnet and closed by an abnormal load or current through said magnet, a second solenoid magnet in alinement with the series magnet connected up by the closing of the 5 switch to cut out the work circuit, and a supplementary core for the second magnet carried by and forming a physical extension of the core of the series magnet, said switch having a preliminary closure effected by the 10 series magnet, the final closure being effected by the action of the second magnet on the supplementary core, the main core of the second magnet being adapted to engage its supplementary core to open said switch positively.

5. In a flat rate controller, the combination of a series solenoid magnet, a main leading thereto, a work circuit fed through the series magnet, an outgoing main leading 20 from the second side of the work circuit, a switch connected with the core of the series magnet and closed by an abnormal load or current through said magnet, a second solenoid magnet in alinement with the series 25 magnet connected up by the closing of the switch to cut out the work circuit, and a supplementary core for the second magnet carried by and forming a physical extension of the core of the series magnet, said switch 30 having a yielding spring contact which engages the opposed contact under the action of the series magnet and which yields under the action of the second magnet on the supplementary core to permit the switch proper 35 to engage the contact, and the main core of the second solenoid magnet being adapted to engage its supplementary core to open said switch.

6. In a flat rate controller, the combination of a series solenoid magnet, a main leading thereto, a work circuit fed through the series magnet, an outgoing main leading 40 from the second side of the work circuit, a switch connected with the core of the series magnet and closed by an abnormal load or current through said magnet, a second solenoid magnet in alinement with the series magnet connected up by closing the switch to 45 cut out the work circuit, and a supplementary core for the second magnet carried by and forming a physical extension of the core of the series magnet, said switch having a yielding spring contact having an engaging curled end which engages the opposed 50 contact under the action of the series magnet and which yields under the action of the second magnet of the supplementary core to permit the switch proper to engage the contact, and the core of the second solenoid 55 magnet being adapted to engage its supplementary core to open said switch.

7. In an automatic electric switch, the combination of a solenoid magnet, a main connected thereto, a work circuit connected 60 to the main, an outgoing main leading from

the second side of the work circuit, a switch connected with the core of the solenoid magnet and closed thereby, a second solenoid magnet in alinement with the first magnet connected up by the closing of the switch to 70 affect the work circuit, and a supplementary core for the second magnet carried by and forming a physical extension of the core of the first magnet, the main core of the second solenoid magnet being adapted to engage its 75 supplementary core and thereby open said switch positively.

8. In an automatic electric switch, the combination of a solenoid magnet, a main connected thereto, a work circuit connected 80 to the main, an outgoing main leading from the second side of the work circuit, a switch connected with the core of the solenoid magnet and closed thereby, a second solenoid magnet in alinement with the first solenoid magnet connected up by the closing of the switch to affect the work circuit, a supplementary core for the second magnet carried by and forming a physical extension of the core of the first magnet, and mechanism for 85 adjusting the position of the supplementary core of the second magnet, the main core of the second solenoid being adapted to engage its supplementary core to open said switch 90 positively.

9. In an automatic electric switch, the combination of a solenoid magnet, a main connected thereto, a work circuit connected to the main, an outgoing main leading from 100 the second side of the work circuit, a switch connected with the core of the magnet and closed thereby, a second solenoid magnet in alinement with the first magnet connected up by the closing of the switch to affect the work circuit, and a supplementary core for 105 the second magnet carried by and forming a physical extension of the core of the first magnet, said switch having a preliminary closure effected by the first magnet, the final closure being effected by the action of the 110 second magnet on the supplementary core, the main core of the second magnet being adapted to engage its supplementary core to open said switch positively.

10. In an automatic electric switch, the combination of a solenoid magnet, a main connected thereto, a work circuit connected to the main, an outgoing main leading from the second side of the work circuit, a switch connected with the core of the solenoid magnet and closed thereby, a second solenoid magnet in alinement with the first magnet connected up by the closing of the switch to affect the work circuit, and a supplementary core for the second magnet carried by and forming a physical extension of the core of the first magnet, said switch having a yielding spring contact which engages the opposed contact under the action of the first magnet and which yields under the action 115

of the second magnet on the supplementary core to permit the switch proper to engage the contact, and the second core of the second solenoid magnet being adapted to engage its supplementary core to open said switch.

11. In an automatic electric switch, the combination of a magnet, a main connected thereto, a work circuit connected to the main, an outgoing main leading from the second side of the work circuit, a switch closed by said magnet, a second magnet connected up by the closing of the switch to affect the work circuit, and means operated by said magnet to open said switch positively and mechanically and permit the automatic restoration of the current through the work circuit.

12. In an automatic electric switch, the combination of a solenoid magnet, a main connected thereto, a work circuit connected to the main, an outgoing main leading from the second side of the work circuit, a switch connected with the core of said magnet and closed by the movement thereof, a second solenoid magnet in alinement with the first magnet connected up by the closing of the switch, a shunt circuit including said switch and second magnet, a second switch operated by the second magnet to open the work circuit, the core of the second solenoid being adapted to engage the core of the first solenoid to open said first switch positively and permit the restoration of the current through the work circuit.

13. In an automatic electric switch, the combination of a solenoid magnet, a main connected thereto, a work circuit connected to the main, an outgoing main leading from the second side of the work circuit, a switch connected with the core of the solenoid and closed by the movement thereof, a second solenoid magnet in alinement with the first solenoid magnet connected up by the closing of the switch, a shunt circuit including said switch and second magnet, and a second switch operated by the second magnet to open the work circuit, the core of the second solenoid magnet being adapted to engage the core of the first solenoid magnet to open said first switch positively and permit the restoration of the current through the work circuit, a dashpot in alinement with the cores of the magnets, and a piston for said dash-

pot carried by the core of the second solenoid and operating to retard its movement. 55

14. In an automatic electric switch, the combination of a solenoid magnet, a main connected thereto, a work circuit connected to the main, an outgoing main leading from the second side of the work circuit, a switch closed by said solenoid magnet, and a second solenoid magnet with its core in axial alinement with the first solenoid magnet so that when the core of the second magnet is moved it will at the end of its movement engage 65 the core of the first magnet to open the switch.

15. In an automatic electric switch, the combination with a solenoid magnet, of a main connected thereto, a work circuit connected to the main, an outgoing main leading from the second side of the work circuit, a switch closed by the action of said magnet, a second solenoid magnet with its core in axial alinement with the core of the 75 first magnet, a member adjustably threaded into one of said cores so that the time of the striking of the core of the first magnet by the core of the second magnet to open the first switch can be regulated, and mechanism 80 for regulating the rate of separation of said cores when the circuit is broken through both of said magnets.

16. In an automatic electric switch, the combination of a magnet, a main connected thereto, a work circuit connected to the main, an outgoing main leading from the second side of the work circuit, a switch connected to the armature of the magnet and closed by the movement of the armature, a second 90 magnet in a shunt circuit closed by the switch, and a second switch connected to the armature of the second magnet serving to open and close the work circuit, said armatures being so relatively located that the 95 armature of the first magnet is engaged by the armature of the second magnet to open the first switch positively.

In witness whereof, I have hereunto set my hand and affixed my seal, this 12th day 100 of March, A. D. 1907.

FRANK KRAEMER. [L. S.]
